(57) **CLAIM**

I claim the ornamental design for a safety light device, as shown and described.

DESCRIPTION

FIG. 1 is a top perspective view of a safety light device, with a pair of teeth in an extended position, showing my new design;

FIG. 2 is a top plan view of the safety light device with a pair of teeth in an extended configuration;

FIG. 3 is a top plan view of the safety light device with a pair of teeth in a retracted configuration;

FIG. 4 is a bottom plan view of FIG. 2 thereof;

FIG. 5 is a right side elevation view thereof;

FIG. 6 is a left side elevation view thereof;

FIG. 7 is a front elevation view thereof; and,

FIG. 8 is a rear elevation view thereof.

The broken lines in the drawings depict portions of the safety light device that form no part of the claimed design.

1 Claim, 8 Drawing Sheets
